CLAIM

The ornamental design for serving tray for beverage glasses, as shown and described.

DESCRIPTION

FIG. 1 is a perspective view of a first embodiment of serving tray for beverage glasses;

FIG. 2 is a top view thereof;

FIG. 3 is a right side elevational view thereof, of which the left side elevational view is a mirror image;

FIG. 4 is a bottom view thereof;

FIG. 5 is a front view thereof;

FIG. 6 is a rear view thereof;

FIG. 7 is a perspective view of a second embodiment of serving tray for beverage glasses;

FIG. 8 is a top view thereof;

FIG. 9 is a right side elevational view thereof, of which the left side elevational view is a mirror image;

FIG. 10 is a bottom view thereof;

FIG. 11 is a front view thereof; and,

FIG. 12 is a rear view thereof.

The broken line showing is included for the purpose of illustrating environmental placement and forms no part of the claimed design.
